COVER FOR A STEAM TURBINE DRIVEN ELECTRICAL GENERATING APPARATUS

Charles D. Wilson, West Allis, Wis., assignor to Allis-Chalmers Manufacturing Company, Milwaukee, Wis.

Filed Mar. 17, 1958, Ser. No. 50,070

Term of patent 14 years

(Cl. D76—1)

Fig. 2

Fig. 4

Fig. 1 is a perspective view of a cover for a steam turbine driven electrical generating apparatus showing my new design.

Fig. 2 is a reduced plan view thereof.

I claim:

The ornamental design for a cover for a steam turbine driven electrical generating apparatus, as shown.
